DART FOR TORSO-FITTING LADY'S GARMENT

Louise Armour, Washington, D. C.

Application April 7, 1950, Serial No. 154,603

4. Claims. (Cl. 2—93)

1

This invention relates to a new shape of dart and location of the same, to improve the lines of a suit jacket or any torso-fitting lady's garment, cut without side seams or with side seams removed two or more inches to the rear of the under arm. The invention also includes a garment employing this dart.

A lady's jacket or any other torso-fitting garment, if it is to be fitted in at the waistline, must provide added material in the region of the bust. This is supplied by providing additional length of material over the point of the bust from shoulder to waistline, and extra width of material over the bust point in a transverse direction. It follows that in regions other than the bust area there will be fullness which must be taken up. The fullness that results from added width of material is ordinarily removed by means of a dart extending from the front of the shoulder downward toward the point of the bust, and by means of another dart which extends from the waistline vertically upward toward the bust point.

The fullness which follows from added length of material usually results in the waistline being lower at the side than beneath the bust, which fault is customarily corrected by cutting the material to provide for a longitudinal side seam extending from the bight of the arm scye to the waistline, and providing either a horizontal dart extending inward from the cut edge of said side seam toward the bust point at the level of the bust point, or an inclined dart extending from a lower point of said side seam toward the bust point.

One of the objects of the invention is to provide a dart so shaped and located as to incorporate the same advantages of the combination under arm side seam and either the horizontal or inclined dart extending therefrom as above described, and to take the place of this combination without requiring the presence of the under arm side seams. Since many ladies' jackets and other torso-fitting garments are more advantageously cut with the side seam eliminated or moved from its normal under arm position to one, three or four inches to the rear of said normal position, the present invention makes it possible to improve both the fit and appearance of such garments, and to simplify the method of their manufacture.

Another object of the invention is to provide a dart which in itself provides the sole means necessary for alteration of the ready-made garment, should the customer find it to misfit at the waistline, or be too large at the hip, or too long,

2

or too short from the arm scye to the waistline. The fact that this one dart alone need be altered to secure the above corrections facilitates alterations by the retail store and thereby enhances mass production possibilities of the garment.

Other objects of the invention will appear as the following description of a preferred and practical embodiment thereof proceeds.

In the drawing which accompanies and forms 10 a part of the following specification, and throughout the figures of which the same reference characters have been used to denote identical parts:

Figure 1 is a perspective view of a garment 15 embodying the concept of the invention;

Figure 2 is a plan of the pattern for half the garment;

Figure 3 is a diagrammatic view of a pattern 20 showing the conventional darts employed for taking up fullness surrounding the bust area.

Referring now in detail to the several figures, and advertizing particularly to Figure 2, the numeral 1 represents as a whole the unassembled pattern for one-half the garment on the cloth itself and shown flat. This pattern is in two parts, 25 3 and 4, the front part 3 indicating by the broken line 5 the normal position of the under arm side seam which is not present in this garment, and the broken line 6, representing the position of 30 the natural waistline. The cross 7 represents the bust point.

The numeral 8 represents the rear edge of the part 3 which is to be brought into coincidence with the forward edge 9 of the part 4, and the 35 edges sewn together to form which may be termed a side seam, but displaced several inches to the rear of the normal location of the under arm side seam, which in the conventional garment extends downward from the lowermost point of

40 the arm scye to the lower end of the garment in a plane perpendicular to the plane of the waistline. It is assumed that added length and width of material has been supplied to the part 3 to accommodate the bust prominence, the apex of 45 which is at 7. The conventional dart 10 is provided for reducing the width of the material above the bust region. Referring to Figure 3, one finds the conventional dart 11 which extends from the waistline vertically upward toward the bust point for taking up the width fullness in the region below the bust area. This is not shown in Figure 2, for it is one of the darts the function of which is performed by the dart of 50 the subject invention.

55 This dart, which is designated by the numeral

12, is an opening which starts at or below the bust point 7, curves downwardly and rearwardly toward the waistline, and then follows the line of the hip as far down as the widest portion of the hip on a long garment, or to the bottom edge of a short jacket, terminating in the line 5. This dart in the preferred form shown in Figure 2, terminates at its upper and lower ends in tails 13 and 14 of hairline thickness, and gradually broadens between said tails to the desired width. The tails are substantially parallel and extend oppositely in the general direction of the warp of the fabric. The center, inclined, and open portion of the dart extends more or less biaswise of the fabric and crosses the waistline. By more or less increasing or eliminating the width of this center opening, depending upon where the modification of its width is made, adjustment either in the length of the material from arm eye to waistline, or adjustment of the waistline, or width over the hip in the case of a long garment, is effected.

In the drawing, the side edges of the material that defines the dart have a smooth reverse or S curvature. Alteration of the width of the dart opening by cutting the material of either edge incidentally changes the length of the cut edge relative to the opposite edge, but since the open portion of the dart extends biaswise of the material, there is no difficulty in stretching the shorter side to the length of the longer side when bringing the edges together in a linear seam.

The following is a summary of the principal advantages of the dart and its principal uses.

(a) To be used principally in ladies' form fitting jackets or other ladies' torso-fitting garments that do not have side seams, or where the side seam is two inches or more to the rear of the under arm point.

(b) To improve the fit of such garments by allowing additional length of material to pass over the bust point without having the same additional length continuing laterally of the bust and under the arm, where there is no prominence of the breast to take it up; also to nip in the waistline and round to the desired curve over the hip line.

(c) To facilitate subsequent alterations on garments incorporating this dart, by allowing in one easy-to-reach dart, quick alterations to improve the fit at any one of the points mentioned in paragraphs (a) and (b).

While I have in the above description disclosed what I believe to be a preferred and practical embodiment of the invention, it will be understood by those skilled in the art that the precise shape or curvature of the edges of the material defining the dart are not to be regarded as absolutely critical, so that they may be varied somewhat without transcending the scope of the invention.

What I claim as my invention is:

1. In a lady's torso-fitting garment, a dart comprising an opening having acute opposite ends, one terminating beneath the bust point adjacent thereto and the other terminating below the waistline at a point in a line extending downward from the lowermost point of the arm scye in a plane perpendicular to the plane of the waistline, said opening being progressively widened from each end towards the middle, the intermediate part of said opening being intersected by the waistline.

2. In a lady's torso-fitting garment of the type in which the side seam is displaced rearwardly of the line of the conventional side seam which extends downward from the lowermost point of the arm scye in a plane perpendicular to the plane of the waistline, a dart comprising an opening having acute opposite ends, one terminating beneath the bust point adjacent thereto, the other at a point below the waistline in a line of the conventional side seam, said opening being progressively widened from each end toward the middle, the intermediate part of said opening being intersected by the waistline.

3. In a lady's torso-fitting garment, a dart comprising an opening having acute opposite ends terminating in slits extending warpwise, one ending beneath the bust point adjacent thereto, the other at a point below the waistline in a line extending downward from the lowermost point of the arm scye in a plane perpendicular to the plane of the waistline, said opening being progressively widened from each slit toward the middle, the edges of said opening being reversely curved, said opening between said slits lying biaswise of the material.

4. In a lady's torso-fitting garment of the type in which the side seam is displaced rearwardly of the line of the conventional side seam which extends downward from the lowermost point of the arm scye in a plane perpendicular to the plane of the waistline, a dart comprising an opening having acute opposite ends terminating in slits, one ending beneath the bust point adjacent thereto, the other at a point below the waistline in the line of the conventional side seam, said opening being progressively widened from each slit toward the middle, the edges of said opening being reversely curved, said slits lying in the direction of the warp and the widened part lying biaswise of the material.

LOUISE ARMOUR.
